(57) **CLAIM**

The ornamental design for a battery enclosure, as shown and described.

DESCRIPTION

FIG. 1 is an isometric view of a top, left, and front side of an ornamental design for a battery enclosure; FIG. 2 is an isometric view of a bottom, right, and rear side of the battery enclosure of FIG. 1; FIG. 3 is a front elevational view of the battery enclosure of FIG. 1; FIG. 4 is a rear elevational view of the battery enclosure of FIG. 1; FIG. 5 is a right side elevational view of the battery enclosure of FIG. 1; FIG. 6 is a left side elevational view of the battery enclosure of FIG. 1; and, FIG. 7 is a top plan view of the battery enclosure of FIG. 1. The dash-dash-dash broken lines are included for the purpose of illustrating portions of the battery enclosure that form no part of the claimed design. The dash-dot-dash-dot broken lines define boundaries of the claimed design and form no part of the claimed design.

1 Claim, 7 Drawing Sheets
